(57) CLAIM

The ornamental design for a hooded sleeping bag, substantially as shown and described.

DESCRIPTION

FIG. 1 is a front view of a hooded sleeping bag, showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front view of a second embodiment of the hooded sleeping bag, showing an expanded lower portion; and,

FIG. 8 is a rear view of FIG. 7.

The broken lines in FIG. 6 represent the portions of the sleeping bag, which form no part of the claim design. The remaining broken lines, shown throughout the views, represent stitching and form no part of the claim design.

1 Claim, 6 Drawing Sheets
